UNITED STATES PATENT OFFICE.

CHARLES EDWARD HAVILAND, OF LIMOGES, FRANCE.

DESIGN FOR A EWER.

SPECIFICATION forming part of Design No. 20,848, dated June 23, 1891.

Application filed May 25, 1891. Serial No. 394,067. Term of patent 14 years.

To all whom it may concern:

Be it known that I, CHARLES EDWARD HAVILAND, a citizen of the United States, residing at the city of Limoges, in the Republic of France, have invented and produced a new and original Design for a Ewer and other Articles, of which the following is a specification, reference being had to the accompanying drawing, forming part thereof and showing a side view of a ewer bearing my design.

In the drawing, A designates the ewer, and B the handle thereon, the latter being formed of the ornamental scroll-sections C D E. The outwardly-flaring mouth of the ewer is provided with the ornate flutings F, terminating

toward the handle B in the curved edge scroll G. Upon the body of the ewer are provided at suitable intervals the ornamental scrolls H, somewhat segmental in outline and having the irregular edge shown, and between the scrolls H are conventionalized foliate sprays I.

What I claim is—

The design for a ewer or other article, substantially as shown and described.

Signed at the city of Limoges, in the Republic of France, this 12th day of May, 1891.

CHARLES EDWARD HAVILAND. [L. S.]
